UNITED STATES PATENT OFFICE.

JAMES GEORGE HOOPER AND FREDERICK RICHARD HOBLEY, OF VAN, NEAR LLANIDLOES, WALES.

ELECTRICAL INDICATOR AND LIKE APPARATUS.

1,308,590.

Specification of Letters Patent.

Patented July 1, 1919.

Application filed June 5, 1918. Serial No. 238,409.

To all whom it may concern:

Be it known that we, JAMES GEORGE HOOPER and FREDERICK RICHARD HOBLEY, subjects of the King of England, and both 5 residents of Van, near Llanidloes, in the county of Montgomery, Wales, have invented certain new and useful Improvements in Electrical Indicators and like Apparatus, of which the following is a specification.

10 This invention relates to electrical indicating apparatus of the known type for the transmission of orders and like signals in which a rotary-field device is employed as the indicator and has the junction points 15 of its coils connected to tappings on a controller circuit that is closed and that is provided with a switch by whose means an electromotive force is applied across two selectively adjustable points in the said 20 closed circuit. It has been proposed to use this type of apparatus for the transmission of order signals, but we have found difficulty in so constructing it as to give very fine indications.

25 The present invention provides indicating apparatus of the type defined, wherein the motor-portion of the indicator comprises coils connected together as in a three-phase rotary field system and mounted on a non-magnetic support to rotate in a magnetic field; a non-magnetic support is selected in order to avoid the effect of hysteresis upon 30 the indications.

According to another feature the controller circuit is arranged as two lengths 35 of resistances extending side by side with one another and having their four extreme ends cross-connected, the far end of one to the near end of the other, and the controller switch is movable along the said 40 lengths to apply the electromotive force across a point on one and a point on the other just opposite to the first.

By way of more clearly indicating the 45 nature of this invention, it is hereinafter described by reference to the accompanying drawings, in which—

Figure 1 is a typical diagram of the electrical circuits of the apparatus;

50 Fig. 2 is a diagram of an alternative arrangement;

Fig. 3 is a perspective view of a controller;

Fig. 4 is a perspective view of an indicator, constructed according to this inven-

tion, controlled by the controller of Fig. 3, and

Fig. 5 is a diagram of a modified arrangement of electrical circuits.

The diagram of Fig. 1 shows the known 60 arrangement of a controller circuit A in the form of a circular resistance circuit, closed upon itself to constitute an annulus, with a controller switch B rotatable about the center of the annulus to make sliding 65 contact by its two contacts B_1 , B_2 with the annulus at opposite ends of a diameter thereof.

Slip rings B_3 , B_4 are provided, and the contact B_1 is connected to the ring B_3 , and 70 the contact B_2 to the ring B_4 by brushes; the contacts B_1 , B_2 are insulated from one another.

A battery B_5 is connected across the slip rings.

The annulus is made of wire of uniform 75 size and quality throughout its length and is evenly wound. At three equidistant points tappings are made and are connected each to one of the junction points of a 80 three-coil closed-circuit rotary-field device, whose coils are indicated at G_1 , G_2 , G_3 . The device is diagrammatically shown as mesh-wound; it may equally well be star-wound or otherwise wound provided it affords 85 three points that are electrically and electromagnetically symmetrical. Thus, if it is wound with a simple 3-phase three-coil star winding, the three free ends of the coils will clearly be the points to be connected 90 one to each tapping T_1 , T_2 , T_3 described below. The coils G_1 , G_2 , G_3 combine to produce a resultant field whose direction is determined by the angular position of the switch B about its center of rotation. Con- 95sequently, rotation of the switch causes rotation of the field, and any device whose position can be controlled by the direction of the resultant field of G_1 , G_2 , G_3 is added, so as to be subjected to that field and to 100 indicate its direction. Such a device is indicated in diagram by a pivoted magnet g .

In practice, however, the moving element must not contain magnetic material. This constitutes the indicator member of the in- 105 dicator formed by the parts G_1 , G_2 , G_3 and g , and always takes a position about its pivot, determined by the position of the switch B about its pivot.

A modified construction of controller 110

- shown in Fig. 2 comprises two parallel lengths of resistance a whose ends a_1, a_2, a_3, a_4 are cross-connected as shown. These are bridged by a switch-arm b making sliding contact at its ends with the two lengths a, a and applying to them at the contact points the electromotive force of a battery diagrammatically shown as carried upon the arm b . Electrically equidistant tappings T_1, T_2, T_3 are taken from the lengths a, a , the tapping T_1 coinciding with the end a_3 of one length, and the three tappings are connected to the three terminals of a rotary-field device g_1 .
- In this construction the switch-arm has a limited rectilinear movement as contrasted with the unlimited circular movement of the switch of Fig. 1. The indication, however, is by angular movement of the indicator member of the device g_1 .
- The apparatus shown in Fig. 3 comprises a controlling sleeve A_7 rotatable about a center pillar A_8 on a base A_4 . Upon the sleeve A_7 is mounted a disk E constituting primarily a switch-arm from which two extensions E_3, E_4 extend downwardly to provide a switching action hereinafter described. On the base A_4 are two contact rings E_1, E_2 and around its outer edge are three concentric rings of contact studs F_1, F_2, F_3 , the members of one ring being staggered relatively to those of its next outer neighbor so that a stud on the innermost ring is intermediate, circumferentially, between one on the middle and one on the outermost rings. The extension E_3 carries a brush at its inner heel bearing constantly upon the ring E_1 and three brushes at its outer end bearing on the three rings of studs F_1, F_2, F_3 ; the arrangement of these studs and the brushes on the extension E_3 is such, however, that the latter only makes conducting contact with one stud at a time except momentarily in passing from one to the other. This arrangement in coöperation with the staggered order of the studs gives a finely sub-divided gradation of the point of contact of the arm E_3 with the studs F_1, F_2, F_3 . The extension E_4 has a similar construction with a brush at its inner heel bearing on the ring E_2 and three brushes at its outer end bearing on the contacts F_1, F_2, F_3 . The extensions E_3, E_4 are also conductively connected by wires supported on the sleeve A_7 to any desired apparatus also carried by the sleeve A_7 , but not forming part of the present invention.
- A battery is permanently connected across the rings E_1, E_2 .
- Between the studs F_1, F_2, F_3 are connected resistances, all equal to one another, so that these three concentric rings of studs provide the electrical equivalent of the annulus A of Fig. 1; that is herein called the resistance F .

The indicator is shown in Fig. 4 and comprises a drum J of non-magnetic material, e. g. aluminium, provided with three pancake coils, of which one only, J_1 , is marked in the drawing, the coils being mounted to revolve within the embrace of a permanent magnet K on a vertical spindle J_2 about the axis P_2-P_2 and constituting with the magnet K a rotary field device.

It will be observed that the rotating portion of this indicator is entirely constructed of non-magnetic material at least where it lies within the sphere of the magnetic field, so that there is no effect of hysteresis upon the moving parts. This is of great importance where fine and accurate indications are required, such for example as indications within one degree of arc in a rotary apparatus. The particular piece of mechanism comprising the indicator is selected by this invention for application to indicating apparatus of the kind defined in order that such an apparatus may give superior results to those hitherto obtained, the said superiority being in fineness of indication and in accuracy in spite of reversals of movement. In short, the selection of the said known construction avoids the occurrence of those errors in the indications which result from hysteresis in the moving parts.

Three slip rings and brushes N, N_1 serve to convey current to the moving coils upon the drum J . Suitable terminals for these various brushes are provided on a base O supporting the indicator. Any desired device, such for example as a pointer, may be mounted on the spindle J_2 .

The connections between the controller and indicator are illustrated in Fig. 1 where the annulus A and the coils G_1, G_2, G_3 correspond respectively with the resistance ring F and the coils J_1 on the drum J . The battery is indicated at B_5 in Fig. 1 and it will readily be understood from the foregoing description that this battery serves to apply a voltage constantly to the rings E_1, E_2 . This voltage is then applied by the switch-arms E_3, E_4 to the resistance F at points that are selectively adjustable and determined by the position of the sleeve A_7 about the axis A_2 . The voltage need not be of constant value; variations in its magnitude do not vary the indications of the indicator.

The electromotive force thus applied to the two selected points on the resistance ring is transmitted from the three tapping points to the three junction points of the coils on the rotary-field device so that the drum J receives a movement of rotation until it takes up a position corresponding with the angular position of the arms E_3, E_4 .

The arrangement shown in Fig. 2 offers a construction which allows the switch to have a movement of translation instead of one of rotation. Alternatively, the ends of

the lengths a a may be connected a_1 to a_3 and a_2 to a_4 , instead of being cross-connected and two contact makers arranged, one for each length, so connected together that as one 5 moves in one direction the other moves in the opposite direction, to apply the electromotive force of the battery across two points so that the resistance through the controller circuit from one of these contacts to the 10 other has always the same value.

Obviously, instead of the battery B_5 , any direct current electrical generator may be employed, and the whole apparatus may be made large and powerful so that the "indicator member" exemplified at g is operated by large forces.

Where it is desired to give to the indicator-member a movement having a less simple relation to the movement of the switch 20 than that obtained by a uniform resistance gradient, the resistance of the controller-circuit may be correspondingly varied from point to point to give the required "gradient". Alternatively the desired result may 25 be obtained by inserting a resistance, which will be termed a corrector, in one or more of the leads connecting the indicator member to the tappings on the controller circuit. Such an arrangement is exemplified dia- 30 grammatically in Fig. 5. In this figure it will be seen that a corrector a_5 is mounted by the side of the controller resistance a a and the switch b is provided with an extension b_1 which makes sliding connection 35 with the corrector a_5 . The contact-piece of the extension b_1 is insulated from the rest of the switch and is connected by a flexible connection q to one terminal of the indicator member and one end of the corrector 40 is connected to the point T_1 of the controller circuit. This said terminal of the indicator member therefore is connected to the tapping point T_1 through a portion of the corrector a_5 the amount of which portion 45 is determined by the position of the switch b . If desired the corrector a_5 may be mounted on a base movable relatively to the controller circuit a a in the direction of the path of the switch; such a mounting is indi- 50 cated in Fig. 5. By this means, as will readily be understood, the precise effect of the corrector may be adjustably varied because the amount of resistance a_5 included at any given position of the switch b may 55 be thus varied. In order to permit of the relative motion between the corrector and the controller circuit the connection between the two is effected by a flexible connection q_2 .

Obviously the corrector may be inserted 60 in any or all of the leads between the tapping points and the indicator member and the precise "gradient" employed in any corrector may readily be determined by those skilled in the art to give any desired "cor- 65 rection"; the gradient may be a constant,

a smoothly varying or an irregular varying one.

The resistance a_5 applies a modification to the indications of the indicator g_1 when such modification is desired. An example of such 70 conditions is found in transmitting instructions for the setting of gun-sights. Without the corrector resistance a_5 the indicator g_1 would merely transmit angular elevation of the target but with the modification introduced by the resistance of a_5 , the indicator g_1 may be made to give corrected tangent elevations. 75

What we claim as our invention and desire to secure by Letters Patent is:— 80

1. In electrical indicating apparatus the combination of, a closed controller circuit, means to apply an electromotive force between two selectively adjustable points in the said controller circuit, means to produce 85 a magnetic field, a three-phase rotary field coil-system carried upon a non-magnetic support rotatably mounted in the said magnetic field, and circuits connecting three terminal points on the said coil-system with 90 three tappings in the said controller circuit, substantially as set forth.

2. In electrical indicating apparatus the combination of, a closed controller circuit, means to apply an electromotive force be- 95 tween two selectively adjustable points in the said controller circuit, means to produce a magnetic field, a three-phase rotary field coil-system carried upon a thin-walled hollow cylinder of non-magnetic metal rotatably mounted in the said magnetic field, and circuits connecting three terminal points on the said coil-system with three tappings in the said controller circuit, substantially as set forth. 100

3. In electrical indicating apparatus the combination of, a closed controller circuit, means to apply an electromotive force between two selectively adjustable points in the said controller circuit, means to produce 110 a magnetic field, a three-phase rotary field coil-system rotatably mounted in the said magnetic field, and circuits connecting three terminal points on the said coil-system with three tappings in the said controller circuit 115 whereof one or more of the said circuits comprises a variable resistance automatically adjusted by means operatively connected with the said means for applying an electromotive force to the controller circuit, 120 substantially as set forth.

4. In electrical indicating apparatus the combination of, a closed controller circuit composed of two substantially straight-line conductor-portions arranged side by side 125 with their respective ends cross-connected one to the other and a switch-member movable with a movement of translation in a path substantially parallel to the said straight-line portions and connected to a 130

source of electromotive force, means to produce a magnetic field, a three-phase rotary field coil-system rotatably mounted in the said magnetic field, circuits connecting three 5 terminal points upon the said coil-system with three tappings upon the controller circuit of which said tappings one or more comprises a substantially straight-line conductor of graded resistance, and means operatively 10 connected with the said means for applying an electromotive force to the controller

whereby the portion of the said graded resistance included in its said circuit is automatically varied, substantially as set forth.

In testimony whereof we have signed our ¹⁵ names to this specification in the presence of two subscribing witnesses.

JAMES GEORGE HOOPER.

FREDERICK RICHARD HOBLEY.
